Nelson M. Howard

UNITED STATES PATENT OFFICE

HARRY L. HOOD, OF EAST LYNN, MASSACHUSETTS, ASSIGNOR TO UNITED SHOE MACHINERY CORPORATION, OF PATERSON, NEW JERSEY, A CORPORATION OF NEW JERSEY

GRINDING MACHINE

Application filed October 18, 1926. Serial No. 142,364.

- This invention relates to abrading machines and is herein illustrated as embodied in a machine for use in grinding the cutting edges of substantially flat, rectangular knives, such, for example, as knives adapted for use in practicing the method disclosed in United States Letters Patent No. 1,527,963, granted February 24, 1925, upon application of J. L. Preo and Isabelle Henne.
10. In accordance with the method disclosed in said Letters Patent, a soled shoe, to which a wooden Louis or similar heel is to be attached, is supported in an inverted position while a knife having a cutting edge disposed 15 at a slight angle to the plane of the bottom of the sole is pushed through the material of the sole in a direction transverse to the length thereof, in the vicinity of the heel breast line. The cut thus formed is not of sufficient 20 depth to extend completely through the sole but serves to form a flap or tongue which is of substantial thickness at its root or base and overlies the overhanging portion of the heel breast adjacent to the attaching face 25 of the heel. This tongue is secured to the overhanging portion of the breast of the heel after the latter is attached and thus provides an anchorage for that part of the heel.
30. One type of knife which may be advantageously used in forming the above described tongue or flap is thin and oblong, having one side plane and flat and the other side somewhat convex transversely of its 35 length. The cutting edge of a knife of this type is generally disposed along one of the narrower sides and is formed by the intersection with the convex side of the knife of a beveled surface formed on the plane flat 40 side of the knife.

With the foregoing considerations in view, the present invention has for an object thereof the provision of an abrading machine for use in producing or reproducing beveled surfaces upon the plane flat sides of knives of the character described, which surfaces will intersect with the convex sides of the knives to form upon each knife a desired cutting edge.

50. In the illustrated embodiment of the in-

vention a grinding wheel is mounted for rotation upon the rotor shaft of a motor and a work holder is mounted adjacent to the grinding wheel in such a manner that a blade supported in the holder may be traversed across the peripheral face of the wheel during the abrading operation, thereby enabling the grinding action to take place progressively along the entire length of the cutting edge.

Inasmuch as the material of which the blade is composed, as well as the abrasive material comprising the grinding wheel, becomes slightly worn during the abrading operation, it is desirable in machines of this character, to provide means for producing relative approach or recession between the work holder and grinding wheel, and it is further desirable that the arrangement be such that the supported knife may be fed with facility in the direction of the grinding wheel while the actual grinding operation is being performed upon the blade.

Accordingly, an important novel feature of the invention resides in the provision of an eccentric feeding arrangement for the work holder, which may be actuated with equal facility during the course of the abrading operation or preparatory thereto. In the illustrated embodiment of the invention the work holder is mounted upon a carrier which is, in turn, mounted for oscillation about an eccentric stud. An arm and an operating lever are connected with the stud in such a manner that movement of the lever results in actuation of the stud and movement of the carrier and work holder toward or away from the grinding wheel.

In the use of the illustrated machine, the knife is generally supported vertically in the work holder and oscillated horizontally across the peripheral face of the grinding wheel, thereby producing a cutting edge lying at right angles to the side edges and to the longitudinal axis of the blade. Such a cutting edge is entirely satisfactory in all instances, but in the single event that the ground knife is to be so used in cutting materials that it must move in the direction of its length, into engagement with, and through, the materials, the cut, while satisfactory, will

be a thrusting one which will cause the cutting edge to dull more rapidly than it would if a slicing cut were effected by an oblique disposal of the cutting edge. In view of this fact a further feature of the invention consists in mounting the work holder in such a manner that it may be moved into either of two positions in one of which a flat cutting edge lying at right angles to the side edges of the blade is produced by the abrading operation and in the other of which a cutting edge obliquely disposed with respect to the side edges of the blade is produced. In the hereindescribed embodiment of the invention this result is accomplished by mounting the work holder in such a manner that it may be tilted about an axis extending at right angles to the axis of oscillation of the carrier and substantially in alinement with the grinding wheel.

Although the invention has been described in its application to a machine for grinding knives for use in practicing the method set forth in said Letters Patent, in various aspects it is not limited to use in grinding knives of that type nor to embodiment in abrading machines of the character illustrated but may be employed in analogous organizations and be useful in performing similar abrading operations.

These and other features and advantages of the invention will appear from a consideration of the following description read in connection with the accompanying drawings and will be pointed out in the claims.

Referring to the drawings,

Fig. 1 is a view in side elevation of a grinding machine embodying the invention, the illustrated machine having parts broken away more clearly to illustrate certain features of construction;

Fig. 2 is a view in front elevation of the grinding machine;

Fig. 3 is a fragmentary view in perspective showing the manner in which the work holder is mounted;

Fig. 4 is a fragmentary view in front elevation showing the manner in which the work holder may be adjusted;

Fig. 5 shows, in perspective, a knife of the type which the illustrated embodiment of the invention is especially designed to grind;

Fig. 6 is a view in front elevation of a blade having its cutting edge disposed obliquely to the side edges of the knife; and

Fig. 7 is a view similar to Fig. 6 showing the cutting edge disposed at right angles to the side edges of the knife.

Referring to the drawings, the numeral 10 indicates a frame for supporting a motor 12 upon the rotor shaft of which is mounted a relatively thin grinding wheel 13. A casting 14 is arranged to enclose a substantial portion of the grinding wheel and serves as a guard to prevent the hands or clothing of

the operative from contacting with that portion of the rotating wheel, as well as a baffle to minimize the danger of injury resulting from flying particles of metal or abrasive produced by the abrading operation.

The illustrated grinding machine is provided with a base upon which is mounted an oscillatory carrier for supporting a blade or work holder in such a manner that the latter may be oscillated, with the carrier, across the peripheral face of the grinding wheel. The base is indicated at 16 and is secured to an arm 18 (which extends laterally from the base of the frame 10) for adjustment along two directions lying at right angles to each other. As illustrated, a slot 20 formed in the arm 18 and a locking bolt 22 permit adjustment of the base 16 in a direction parallel to the axis of the grinding wheel 13, and a slot 26 (Fig. 3) and bolt 24 allow adjustment of the base in a direction at right angles to the axis of the wheel.

The carrier for supporting the work holder is indicated at 28 and is mounted for oscillation across the top surface of the base 16 about a stud 48 the axis of which lies to the rear of the grinding wheel 13 in a plane at right angles to the axis of the grinding wheel. The purpose of mounting the carrier for oscillation in this fashion and the benefits that result therefrom will be hereinafter more fully explained.

The carrier 28 has formed at its forward extremity an upwardly extending wall 30 which is arcuately grooved at 32 to receive a correspondingly shaped ridge formed at the bottom of a work holder 34. The illustrated work holder is provided with a vertically extending slot 36 into which are adapted to be fitted pins 44 (Figs. 5, 6 and 7) formed on the front face of a knife 45 which is thin and oblong, having one side plane and the other convex transversely of its length. Knives of this character are used in forming a tongue or flap along the heel breast line of an outsole, in accordance with the practice of the method disclosed in said Letters Patent. The pins 44 lie at equal perpendicular distances from one of either of the parallel side edges of the blade 45 and it will therefore be appreciated that if the pins are inserted in the slot 36 when the latter is vertically disposed as shown in Fig. 2, the side edges of the blade will also extend vertically and parallel to the side faces of the grinding wheel. With the blade or knife so positioned, horizontal oscillation of the holder and blade across the face of the grinding wheel will result in the formation of a cutting edge lying at right angles to the side edges of the blade.

It may, however, be desirable (as hereinbefore stated), to produce upon the blade a cutting edge lying obliquely to the side edges of the blade (Fig. 6), and to this end

the work holder 34 is mounted, by means of the groove 32 formed in the carrier 28 and the ridge formed on the holder, in such a manner that it may be tilted relatively to the carrier, about an axis lying at right angles to the axis of oscillation of the carrier and substantially in alinement with the grinding wheel 13, as shown in Figs. 2 and 4. A slot 25 located in the base of the work holder 34 cooperates with a bolt 46 in locking the work holder 10 in a desired tilted position. It will be appreciated that horizontal oscillation of the tilted blade across the face of the grinding wheel 13 will result in the production of an oblique cutting edge such as that illustrated in Fig. 6.

15 To cooperate with the slot 36 in holding the knife 45 within the work holder, the latter is provided with an arm 40 tapped to receive a set screw 42 which may be moved 20 into clamping engagement with the knife. An adjustable abutment 38 is located adjacent to the bottom of the slot 36 and serves to regulate the depth to which the knife 45 may be inserted within the holder. By virtue of being able to adjust the heightwise 25 position of the knife relatively to the grinding wheel 13, cutting edges of various angular bevels may be imparted to the blade; it being understood that if the blade be presented 30 to the grinding wheel at a locality on the periphery thereof in the same horizontal plane with the axis of rotation of the grinder that a bevel of greater width will be produced than if the blade be presented to the grinder 35 at a locality upon the periphery lower than the first-named locality.

Inasmuch as the knife 45 is wider than the 40 crowned peripheral face of the grinding wheel 13, it is necessary, in order to grind a cutting edge entirely across the width of the blade, that the blade be traversed across the face of the grinding wheel or, on the other hand, that the grinding wheel be traversed along the cutting edge of the blade. In the 45 illustrated embodiment of the invention the blade is moved relatively to the grinding wheel and is moved in a curved path (by virtue of mounting the carrier 28 for oscillation) instead of in a straight line path.

50 This latter feature is necessary owing to the convex character of the side of the blade upon which the cutting edge is formed. If the blade were moved in a straight line across the face of the grinding wheel, the cutting edge produced would be curved, the median portion of the cutting edge projecting beyond the end portions. It is generally desirable, however, to impart to the blade a flat cutting edge, lying within a plane positioned at 55 right angles to the axis of curvature of the cylindrical surface of the blade or lying at a small angle to such a plane. Accordingly the work holder is mounted for oscillation about a radius equal to the radius of curvature 60 of the rear surface of the supported blade.

Movement of the blade in this manner results in the production of a cutting edge lying within a single plane and appearing as a straight line when projected as in Figs. 6 and 7 upon a plane tangent to the convex surface of the blade. 70

As already pointed out, the slot 26 and bolt 24 constitute means to permit adjustment of the work holder 34 towards or away from the grinding wheel 13. In addition to the foregoing feature of adjustment, the machine is also provided with novel means for feeding or adjusting the work holder towards or away from the grinding wheel, and this provision is such that the holder may be moved with facility during the grinding operation to compensate for the wearing away of the abrading material comprising the wheel or the material of which the blade is made. As illustrated, the stud 48 about which the carrier 28 oscillates is formed with a shoulder portion 66 eccentric with respect to the body portion 68 of the stud and which is encircled by an eccentric strap 67 formed at one end of the carrier. The body 68 of the stud extends through and beyond the end of a bearing formed at one end of the base 16, and to the projecting end of the body is rigidly connected a lever arm 50. An operating rod 52 extends from the arm 50 and passes through a downwardly projecting, forward portion of the base 16. The forward end of the rod 52 is screw threaded to receive a knurled, rotatable operating nut 54. Thus, endwise movement of the rod 52 results in rotation being imparted to the stud 48, thereby causing the carrier 28 and work holder 34 to approach or to recede from the grinding wheel 13. To insure that the operating rod 52 will move rearwardly, when permitted to do so by rotation of the nut 54, a compression spring 56 encircles the rod and, as herein illustrated, abuts at one extremity against a cotter pin 58 positioned in a hole in the rod 52 and at its opposite extremity against the downwardly depending portion of the base 16. 105

Having thus described my invention, what I claim as new and desire to secure by Letters Patent of the United States is:

1. A machine of the character described having, in combination, a grinding wheel, a work holder mounted for oscillation across the peripheral face of the grinding wheel, and means comprising an eccentric and eccentric strap connected to the work holder for producing relative movement between the work holder and the grinding wheel in a direction to cause the work holder to approach or to recede from the grinding wheel. 115

2. A grinding machine of the character described having, in combination, a grinding wheel, a supporting base, a carrier mounted for oscillation relatively to the supporting base, a work holder mounted upon the carrier, and means comprising an eccentric and ec- 125

130

centric strap and connections therefrom to the work holder for moving the work holder toward or away from the grinding wheel.

3. In a grinding machine, a grinding wheel, a work holder, and means for moving the work holder toward or away from the grinding wheel, said means comprising an eccentric, an eccentric strap encircling the eccentric and connected to the work holder, an arm secured to the eccentric, and an operating member secured to said arm movable to rock the arm and thereby to rotate the eccentric.

4. In a grinding machine, a grinding wheel, a work holder, means for moving the work holder toward or away from the grinding wheel, said means comprising an eccentric and eccentric strap, connections therefrom to the work holder, an arm secured to the eccentric, and an operating member secured to said arm, and yielding means tending normally to move said operating member in one direction.

5. In a grinding machine, a grinding wheel, a carrier, a work holder mounted upon said carrier and means for moving said carrier to effect relative approach or recession between said work holder and said grinding wheel, said means comprising an eccentric and eccentric strap connected to the carrier, an arm connected to said eccentric and extending laterally therefrom, a rod connected to said arm, and means mounted upon said rod for giving the rod endwise movement to rock said arm and thereby to rotate the eccentric.

6. A machine of the character described having, in combination, a grinding wheel, a supporting base mounted for adjustment relatively to the grinding wheel, a carrier supported by said base for oscillation transversely of the peripheral face of the grinding wheel, an eccentric, an eccentric strap encircling the eccentric and connected to said carrier, said eccentric being arranged for actuation to produce movement of said carrier relatively to said supporting base, and a work holder mounted upon said carrier.

7. A grinding machine of the character described having, in combination, a grinding wheel, a carrier mounted to oscillate transversely of the peripheral face of the wheel, a vertically extending work holder supported solely by said carrier and mounted for adjustment relatively to the carrier about a horizontal axis extending at right angles to the axis of oscillation of the carrier and substantially in alinement with the grinding wheel.

8. A grinding machine of the character described having, in combination, a grinding wheel, a carrier mounted for oscillation relatively to the grinding wheel about an axis at the rear of the grinding wheel, a work holder mounted upon the carrier in front of the grinding wheel for tilting adjustment about an axis extending at right angles to the axis

of oscillation of the carrier and extending also in substantial alinement with the grinding wheel.

9. In a grinding machine of the character described, a grinding wheel, a carrier mounted for oscillation relatively to the grinding wheel about an axis at the rear of the grinding wheel, a work holder mounted upon the carrier in front of the grinding wheel for movement into either of two positions, in one of which a supported blade will be presented to the grinding wheel with its longitudinal axis lying at a right angle to the axis of the grinding wheel and in the other of which the longitudinal axis of the blade will be obliquely disposed with respect to the axis of the grinding wheel.

10. A machine of the character described comprising, in combination, a grinding wheel, a carrier mounted for oscillation about an axis at the rear of the wheel and lying in a plane extending at right angles to the axis of the grinding wheel, and a work holder mounted upon said carrier in front of the wheel for tilting adjustment about an axis extending at right angles to the axis of oscillation of the carrier, said work holder being provided with a slot running throughout its length to receive projecting portions of the work-pieces to be ground, and means for maintaining a cutting knife within the holder.

11. A grinding machine of the character described having, in combination, a grinding wheel, a base for supporting an oscillatory carrier, a work holder mounted upon said carrier for movement across the periphery of the grinding wheel, and a connection extending between said supporting base and said carrier comprising a stud having a shoulder portion arranged to be encompassed by one extremity of said carrier, and a body portion with respect to which said shoulder portion is eccentric, said body portion being encompassed by one extremity of said supporting base.

In testimony whereof I have signed my name to this specification.

HARRY L. HOOD.
